US0D1038210S

(12) **United States Design Patent** (10) **Patent No.:** **US D1,038,210 S**
(45) **Date of Patent:** ** Aug. 6, 2024

(54) **CAMERA CONTROL DEVICE**

- (71) Applicant: **Blackmagic Design Pty Ltd**, Port Melbourne (AU)
- (72) Inventors: **Grant Petty**, Port Melbourne (AU); **Simon Kidd**, Port Melbourne (AU); **Michael Cornish**, Port Melbourne (AU); **Ryan Harper**, Port Melbourne (AU); **Nathan Lee**, Port Melbourne (AU); **Sophie Koikas**, Port Melbourne (AU); **Daniel Graeme Corcoran**, Port Melbourne (AU); **Jerry Chiang**, Port Melbourne (AU); **Shannon Smith**, Port Melbourne (AU)
- (73) Assignee: **Blackmagic Design Pty Ltd**, Port Melbourne (AU)
- (**) Term: **15 Years**
- (21) Appl. No.: **29/822,513**
- (22) Filed: **Jan. 10, 2022**

(30) **Foreign Application Priority Data**

- Jul. 13, 2021 (AU) 202114150

(57) **CLAIM**

The ornamental design for a camera control device, as shown and described.

DESCRIPTION

FIG. 1 is a perspective view of a camera control device showing our new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The dot-dash broken lines depict contour and not surface ornamentation.

The portions illustrated in dashed broken lines and the portions illustrated within dashed broken lines depict portions of the camera control device which form no part of the claimed design.

1 Claim, 8 Drawing Sheets
